UNITED STATES PATENT OFFICE.

ALPHEUS W. ALTORFER, OF ROANOKE, ILLINOIS, ASSIGNOR TO POWER WASHING MACHINE CO., OF PEORIA, ILLINOIS, A CORPORATION OF ILLINOIS.

DRIVING MECHANISM.

1,078,402.

Specification of Letters Patent. Patented Nov. 11, 1913.

Application filed December 3, 1912. Serial No. 734,688.

To all whom it may concern:

Be it known that I, ALPHEUS W. ALTORFER, a citizen of the United States, residing at Roanoke, in the county of Woodford and State of Illinois, have invented certain new and useful Improvements in Driving Mechanisms, of which the following is a specification.

This invention has reference to improvements in driving mechanisms and has for its object to provide a driving mechanism more especially applicable to the operating means of a washing machine and like structures.

The invention has for a further object a driving mechanism for washing machines and like structures which is power operated and with which the operating means of the washing machine may be moved into and out of operative engagement with said driving mechanism.

The constructions shown in this application are disclosed in my three prior applications, bearing Serial Nos. 533,666; 583,818 and 719,935, respectively.

That the invention may be more fully understood, reference is had to the accompanying drawings, in which:

Figure 1 is a side elevation of a machine support and machine thereon with my mechanism employed for actuating the operating means of said machine; Fig. 2 is an end elevation looking at the right hand end of Fig. 1, the operating means of the machine shown in dotted lines as being in operative relation with said driving mechanism; Fig. 3 is a view similar to Fig. 2, except that the driving mechanism is modified slightly; Fig. 4 is a side elevation of a modified construction of machine support, including a modified driving mechanism for the operating means of the washing machine, and Fig. 5 is an end view of the structure shown in Fig. 4, illustrating by dotted lines how the operating means is moved out of operative engagement with the driving mechanism.

Like characters of reference indicate corresponding parts throughout the figures.

The driving mechanism which I employ is especially applicable to that improved type of washing machine structure, which comprises a machine support on which may be mounted a washing machine or like structure adapted to be driven by power; one or

more tubs or receptacles into which clothes may be wrung from the washing machine and after rinsing, wrung into a receiving receptacle, and a wringing mechanism mounted on said machine support adapted to be driven from the same power which is used for operating the washing machine and which said wringing mechanism is movable with respect to the washing machine and rinsing tub or tubs or receptacles supported by said machine support. It is my aim to actuate the operating means of the washing machine from a driving mechanism which is operated by power; the operating means of the washing machine being of that type which is secured to the top of the machine or the lid or cover therefor and movable into and out of operative relation with said driving mechanism, when the machine is swung on the support for draining the machine or when the lid or cover is swung back on its hinges.

In the drawings, the numeral 1 designates the machine support or main frame, preferably rectangular in form and having the longitudinal side members 2, the end members 3 and the supporting members or legs 4. In Figs. 1, 2 and 3, the frame structure of the support is made of wood, whereas in Figs. 4 and 5 the longitudinal side members 5 are made of angle iron bent at 6 to produce the end supporting members or legs 7 which are integral with the side members 5. When constructing the frame of metal, I employ the longitudinal braces 8 and the transverse braces 9 and 10, also, the diagonal braces 11. The machine support may include a flooring or cross supporting members adapted to support the washing machine, tubs or receptacles, however, such flooring or cross supporting members are not shown in Figs. 1, 2 and 3 but a flooring is shown at 12 in Figs. 4 and 5.

Reference being had to Figs. 1, 2 and 3, 13 designates a driving shaft which is disposed longitudinally of the machine support and alongside of one of the side members 2, and journaled in suitable bearings or boxings 14, suitably attached or secured to the frame of the machine support. On one end of this shaft are carried the pulleys 15 and 16, the latter being the driving pulley for said shaft 13 and said pulley may receive its power in any suitable manner

and from any suitable source of power, and while I have shown the pulley 16 as a single pulley, it is of course understood that it may comprise a fast and loose member on 5 the shaft, with means for shifting the belt or other driving means. The pulley 15 is used for transmitting power from the shaft 13 to the operating means of a washing machine or like structure, in a manner which 10 will be explained.

17 designates a washing machine or like structure, which may be of any approved construction having a lid or cover 18 shown in dotted lines in Figs. 2 and 3 supporting 15 the operating means for actuating the agitator or other mechanism for the interior of the machine, said operating means including the shaft 19 and a driving member or wheel 20. In this instance, said driving 20 member or wheel 20 is shown having a frictional engaging periphery, although said driving member or wheel may be of any other preferred construction and driven other than by frictional means.

25 To actuate the driving member or wheel 20 of the washing machine, a belt 21 is employed, driven by the pulley 15, and said belt 21 travels crosswise of the machine support at one end thereof, passing around an 30 idler pulley 22 carried by a bar 23 pivotally connected or supported at 24 to the cross piece 3; said belt 21 also travels over an idler wheel 25 carried by a bar 26 also secured to said cross piece 3. To produce 35 slack in the belt 21 and that said belt may be maintained in operative position to be engaged by said driving member or wheel 20 and when so engaged to operate the said wheel, a spring 27 is attached at one end to 40 the bar 23 and its opposite end suitably secured to the frame of the support. This form of my invention is shown in Fig. 2. It is obvious from the foregoing that when the shaft 13 is operated it will rotate the 45 pulley 15 and said pulley in turn will actuate the belt 21, which said belt traveling around said pulley 15 and the idler pulleys 22 and 25 is in a position, when the lid or cover of the washing machine is closed to 50 frictionally engage and impart movement to the driving member or wheel 20, which in turn will operate the mechanism within the washing machine 17. To cut out the washing machine and mechanism therein, or to 55 disconnect the operating mechanism of said washing machine, its lid or cover 18 may be raised as shown in dotted lines in Fig. 2, which will move the driving member or wheel 20 out of operative engagement with 60 said belt 21, and said belt may continue to be operated, the operative mechanism may be instantly thrown into use by closing the lid or cover 18, placing the driving member or wheel 20 into operative relation with said 65 belt 21.

I prefer in the driving mechanism of the machine, to include the pulley 25 and support therefor, but it is obvious that this pulley may be done away with if desired.

In Fig. 1, I have shown in dotted lines, a rinsing tub 28 supported on the frame work of the machine support, and a tub or other receptacle 29 into which clothes may be deposited after wringing the same from the tub 28. In Fig. 1, I also show a wringing mechanism indicated generally as 30, which is movably supported on the machine support and adapted to be driven when desired from the driving shaft 13, but as the wringing mechanism forms no part of the invention herein claimed, it is not thought necessary to specifically describe the structure and operation of such wringing mechanism.

In Fig. 3, I have shown a driving mechanism which is in most respects similar to the driving mechanism shown in Fig. 2, except that I employ only one idler pulley 29 which is similar to the idler pulley 22 and support said idler pulley 22 on a bracket 30 which is vertically adjustable on an upright or suitable support 31. The bracket 30 has the slot 32, and 33 is a suitable locking and adjusting means by means of which the bracket when adjusted to different positions, may be locked in such adjusted position. In this figure, in dotted lines, the lid or cover 18 of the machine 17 has been raised to move the driving member or wheel 20 from operative relation with the belt 21.

In Figs. 4 and 5, the driving shaft 34, which is similar to the driving shaft 13 in Figs. 1, 2 and 3, is disposed longitudinally of the machine, but instead of being located alongside of and adjacent a side member 2, said shaft is located centrally of the machine, and on one end carries the pulleys 35 and 36, which are similar and correspond, respectively, with the pulleys 15 and 16 on the shaft 13; said pulley 36 adapted to be driven from any suitable source of power and the pulley 35 adapted to actuate the belt 21. In this structure, the idler pulleys 37 and 38 which are similar to the idler pulleys 22 and 25, are suitably mounted on the upper ends of similar uprights 39 and in such a position that the belt 21, which travels from one idler pulley to the other, may be engaged by the driving member or wheel 20 carried by the lid or cover 18 of the washing machine. In Fig. 5, the lid or cover is shown in dotted lines as raised, removing the driving member or wheel 20 from frictional engagement with the belt 21.

What I claim:—

1. In a machine of the character described, a machine support, a driving shaft, a machine mounted on said support, an operating means for said machine movably mounted thereon and including a shaft and a driving member, a belt adapted to be driven by the

driving shaft and arranged to have a frictional contact with said driving member, and an idler wheel for said belt.

2. In a machine of the character described, 5 a machine support, a driving shaft, a belt adapted to be driven by said shaft, idler wheels for said belt, supports for said idler wheels, a machine mounted on said machine support and having a movable element, an 10 operating means for said machine mounted on said element and including a shaft and a wheel thereon having a frictional engaging surface, said wheel when said element is in one position, arranged to have a frictional 15 engagement with said belt and when in another position to be out of frictional engagement with said belt.

3. In a machine of the character described, 20 a machine support, a driving shaft suitably journaled on said support, two wheels on said shaft, one for receiving power from a suitable source for operating said shaft and the other adapted to drive a belt, a belt arranged to be operated from said shaft, an 25 idler wheel for said belt, a support for said idler wheel, a machine mounted on said machine support, an operating means on said machine, said operating means including a wheel adapted to have a frictional engaging 30 relation with said belt, and supporting

means on the machine for the operating means thereof, said supporting means adapted to be raised and lowered for moving said wheel out of and into engaging relation with said belt.

4. In a machine of the character described, 35 a machine support, a driving shaft extending longitudinally of said support and suitably journaled thereon, a driving member on said shaft, a belt adapted to be driven by said driving member and extending transversely of said support, an idler wheel suitably mounted on said machine support around which said belt travels, a machine 40 mounted on said machine support and provided with an operating means including a shaft and a wheel thereon, having a frictional engaging surface, said wheel arranged to be driven by said belt, and supporting 45 means on said machine for the shaft and wheel of the operating means thereof, said supporting means being movable to adapt a connection and disconnection of said wheel with said belt.

In testimony whereof I affix my signature, 50 in presence of two witnesses.

ALPHEUS W. ALTORFER.
